UNITED STATES PATENT OFFICE.

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

MOLD FOR CENTRIFUGAL PIPE CASTING.

Application filed November 6, 1926. Serial No. 146,612.

My invention relates to the construction of metallic molds for the centrifugal casting of pipe by what is generally known as the De Lavaud process. As heretofore generally constructed the metal mold, usually made from a steel forging, has been formed with radial flanges at its ends, to one of which, in practice, that at the bell end of the mold, the driving mechanism is connected, while to the 10 flange at the opposite end is connected a cylindrical drum in which is formed circumferential packing grooves. Owing to the rapid heating and cooling of molds used in centrifugal pipe casting destructive strains are set 15 up in the metal of the mold, which sooner or later lead to the formation of checks and cracks which impair its usefulness and this tendency of the mold to check or crack under the conditions of use I have 20 discovered to be due to a quite large extent to the presence of the integral radial flanges at the ends of the mold and which flanges not being exposed to the same rapid alternations of temperature as the body of the mold bring 25 about injurious strains.

The object of my invention is to provide a mold, the useful life of which will be materially increased and this increased durability I have discovered can be attained by forming 30 the metallic mold with an external conformation substantially corresponding to its internal conformation and without substantially extending radial flanges at its ends and the leading feature of my invention consists in the provision of such a mold. My invention further consists in securing to one 35 end of the mold formed as above described, preferably to its bell end, a separable radially extending flange to which the mold driving mechanism is or can be attached and through 40 which the mold is driven and by preference I form integral with such a separable flange a core receiving set. A further feature of my invention consists in forming in the unflanged 45 spigot end of the mold one or more packing receiving circumferential grooves.

The nature of my invention will be best understood as described in connection with the drawings in which it is illustrated, and 50 in which

Figure 1 is a sectional elevation of my improved mold and the casing in which it is assembled for use, taken as on the line 1—1 of Fig. 2 but with one of the roller supports for the mold which lies in front of the section 55 shown in section.

Figure 2 is an end view of the apparatus shown in Fig. 1, viewed from the bell end of the mold.

Figure 3 a cross section on the line 3—3 of Fig. 1, and

Figure 4 an end view of the spigot end of the mold.

Figure 5 is a sectional elevation of a modified construction showing modified means for securing separable flanges to both ends of the mold, and

Figure 6 is a sectional elevation of the bell end of a mold showing a further modification of means for securing the separable parts to 70 the mold end.

Referring first to the construction of Figs. 1 to 4:

A indicates the body of the mold; A¹ its bell end, having as shown, a shouldered butt 75 end A². A³ indicates the spigot end of the mold, formed with circumferential packing receiving grooves indicated at a³. B and B¹ are respectively the lower and upper sections of the casing enclosing the mold and serving 80 as a water jacket surrounding the mold. C, C, are supporting rolls on which the mold rests in the casing. D, D¹, are heads formed at the end of the casing through which the spigot end of the mold projects and against 85 which packing rings, indicated at d and d¹, and lying in the peripheral grooves a³, form water tight joints. E is a terminal ring secured to the spigot end of the mold as shown by a split ring F engaged in the peripheral 90 groove A⁴ of the mold. G indicates the end wall of the casing located near the bell end of the mold. H is a driving gear ring on which H¹ indicates the gear teeth, which ring, as shown, is formed integral with a separable 95 flange i, fitting over the butt end A² at the bell end of the mold, as indicated at i¹ and having a shoulder i² which fits against the inside of the shoulder A². At the inner end of the ring H, I have indicated a separable 100

ring K having grooves formed in it in which lie packing rings which form water tight joints with the end plates indicated at G. The flange *i* is, as shown, secured to turn with the mold over which it fits by means of a key indicated at J. *i* is also a separable radial flange having a shoulder *I*¹ which fits against the outer end of the mold. The flange *I* is formed as shown integral with a core seat section, indicated at *I*². As shown, this flange section is formed with an annular shoulder *I*³ fitting in an annular seat in the shoulder *i*. The core seat portion is formed with key slots indicated at *I*⁴ while the flange *I*⁵ portion is, as shown, provided with bolt holes through which extend bolts K screwing into the flange section *i*⁶.

In the particular form of my invention, as illustrated and above described, the place of the customary integral flange at the bell end of the mold is taken by the two flanged parts *I* and *i*, which constitute together a divisional radial flange but it will be understood that the essential feature of my invention consists in providing in place of the integral flange a separable flange through which, and convenient attachments, the mold can be rotated and which being entirely separate from the mold proper permits the rapid expansion and contraction of the mold without subjecting it to the same strains which I have found to exist where the flange is an integral part of the mold.

In the modification shown in Fig. 5, the spigot end *A*³ of the mold is threaded as shown at *a*³ and the butt end of the bell is also threaded as shown at *a*². A flange *i*,*i*, is secured on the spigot end and formed with a ring or drum extension *i*,*i*¹, to which is keyed a driving pulley *H*,*H*, and which is formed with grooves to receive packing rings *d*,*d*¹, fitting against the end walls *D*,*D* and *D*,*D*¹. At the bell end of the mold a separable part forming a flange *I*,*I*, and core seat *I*,*I*², is secured on the end of the mold with a shoulder *I*,*I*¹ abutting against the end. The flange *I*,*I* is grooved to receive packing rings *b*⁶, which fit against the end walls *G*,*G* of the casting.

In Fig. 6 a flange *i*,*i*,*i*, is keyed to the butt end *A*² of the mold and formed with a threaded extension *i*,*i*,*i*⁴ into which screws a ring *I*,*I*,*I*, which forms a core seat *I*,*I*,*I*², and has a shoulder *I*,*I*,*I*¹, which fits against the end of the mold and coacts with shoulder *i*,*i*,*i*¹ on flange *i*,*i*,*i*, in securing the composite flange to the end of the mold. A set screw L serves to secure the parts *i*,*i*,*i* and *I*,*I*,*I*² together. A ring or drum extension *H*,*H*,*H*, supports any driving mechanism not shown.

It will be understood that the essential features of my invention consist in providing an unflanged mold and separable means for making the usual attachments at the ends of

the mold. The specific forms shown may be taken as illustrative and not, except where specifically called for in the claims, as essential features of my invention.

By dispensing with the generally used flange at the spigot end of the mold, as in Fig. 1, I avoid strains due to rapid expansion and contraction at this end of the mold and by providing the packing grooves in the cylindrical body of the mold I am enabled to secure a water tight joint in a simple and efficient manner and without the employment of the flange and drum heretofore generally used at this end of the mold.

Having now described my invention, what I claim as new and desire to secure by Letters Patent is:

1. A bell ended metal mold for centrifugal casting of pipe, the external conformation of the bell end substantially corresponding to its internal conformation in combination with a separable part comprising a radial flange and core seat and means for attaching said separable part to the bell end of the mold.

2. A metal mold for the centrifugal casting of pipe having the internal conformation of the exterior of the pipe to be formed in it, said mold having an unflanged spigot end with one or more recessed packing grooves formed on its outer face.

3. A bell ended metal mold for centrifugal casting of pipe, having the internal conformation of the pipe to be formed in it and an external conformation substantially corresponding from end to end to its internal conformation, the spigot end of said mold having one or more circumferential packing grooves formed in it in combination with a separable radial flange and means for attaching said flange to the bell end of the mold.

4. A metal mold for the centrifugal casting of pipe, formed without substantial radial flanges at its ends in combination with a separable radial flange for the attachment of driving means and means for securing said flange to one end of the mold.

5. A metal mold for the centrifugal casting of pipe, formed without substantial radial flanges at its ends in combination with a separable radial flange for the attachment of driving means, a driving gear ring attached to said flange, and means for securing said flange to one end of the mold.

6. A metal mold for the centrifugal casting of pipe, formed without substantial radial flanges at its ends in combination with a driving ring and means for attaching said ring to an unflanged end of the mold.

7. A pipe mold consisting of a tubular shell of uniform thickness throughout its length, removable end rings therefor, and means to secure said rings in place on said shell.

8. A pipe mold tube the wall of which is of substantially uniform thickness throughout

its entire length, and a driving ring remov- mold is revolvably supported with its ends
ably secured around the exit end of said extending beyond the water jacket, a separ-
mold tube. able radial flange attached to one end of the 10

9. A machine for the centrifugal casting mold and means for rotating the mold oper-
5 of pipes, comprising a metal mold formed atively connected therewith through said
without substantial radial flanges at its ends, separable flange.

JOHN H. UHRIG.
